UNITED STATES PATENT OFFICE.

JOSEPH PRONOVOOST, OF DETROIT, MICHIGAN.

SPRING-FRAME FOR VEHICLE-WHEELS.

1,271,360.

Specification of Letters Patent.

Patented July 2, 1918.

Application filed October 19, 1917. Serial No. 197,477.

To all whom it may concern:

Be it known that JOSEPH PRONOVOOST, a citizen of the United States, residing at Detroit, in the county of Wayne and State 5 of Michigan, has invented certain new and useful Improvements in Spring-Frames for Vehicle-Wheels; and he does hereby declare the following to be a full, clear, and exact description of the invention, such as will 10 enable others skilled in the art to which it appertains to make and use the same, reference being had to the accompanying drawings, and to the letters and figures of reference marked thereon, which form a part of 15 this specification.

This invention relates to new and useful improvements in spring frames for use upon vehicle wheels, with a view of affording efficient means to take up vibration incident to 20 a wheel passing over rough roads or obstacles, and serving as a substitute for a pneumatic tire.

The present invention consists in the provision of a device of this nature, having 25 various details of construction and combinations of parts, and generally improving upon the form of spring apparatus covered by my Patent #1,220,889.

The present invention is illustrated in the 30 accompanying drawings, which with the letters of reference marked thereon, form a part of this specification and in which:

Figure 1 is a side elevation showing the application of my invention.

Fig. 2 is a perspective view of the spring frame, and

Fig. 3 is a detailed perspective view.

Reference now being had to the details of the drawings by letters:

40 A and B designate two U-shaped members, which are adapted to telescope one within the other, having relative longitudinal sliding members. The member A is provided with oppositely disposed elongated 45 slots A', each slot terminating at corresponding ends in a circular outlined portion A². The member A has one end bent, as at A³, and has a concaved portion A⁴ and an end portion A⁵ bent parallel to the oppositely disposed elongated portions of the member 50 and engages an inwardly turned portion A⁶ near the other end of the member. The second end of the member A is concaved,

or hook-shaped, as at A⁷, and rests against the inner convexed portion of the hooked 55 end.

The member B has oppositely disposed slots B' and at corresponding ends opposite those in the member A has circular outlined portions B². A movable cross-piece or block 60 D has oppositely disposed recesses E, the portions of the block intermediate said recesses being adapted to be guided in the registering slots in the two members A and B. The opposite faces of said block, intermediate the two members A and B, are concaved, as at F, the recess upon the outer face of the block being adapted to contact with a pin or roller H, adapted to be connected 65 to the disk or hub portion H' of a wheel. 70

A spring, designated by letter N, is bent at its longitudinal center, forming a cross-piece O, which engages the hooked end of the member A, the arms of the wire being 75 bent to form coils R, and the free ends of the wire are passed through registering slots in the two members A and B, and the angled ends T of the wire, which extend in opposite directions, engage the concaved recess in the face of the block D holding the latter 80 against the inwardly turned ends B³ of the member B. A pin or roller, designated by letter S, is adapted to be positioned intermediate the concaved recess formed in the member A and the adjacent concaved portion 85 of the member B.

It will be noted upon reference to the drawings that the angled ends T of the spring extend around the corners intermediate the two concaved surfaces and interlocking therewith in such a manner as to prevent the device rattling, and affording substantial means for holding the ends of the wire in proper relation with the block. 90

What I claim to be new is:

1. A spring frame for vehicle wheels, comprising two U-shaped members having sliding connection with each other and provided with oppositely disposed registering slots, the ends of the inner of said members being bent to over-lap each other in opposite directions, a block having contracted portions movable within said slots, a coiled spring bent upon itself at its longitudinal center and engaging the inner of said bent 100 ends, the arms of the wire extending 105

- through registering slots in said members and having ends bent in opposite directions and engaging the inner face of said block.
2. A spring frame for vehicle wheels, comprising two U-shaped members having sliding connections with each other and provided with oppositely disposed registering slots, the ends of the inner of said members being bent to over-lap each other in opposite directions, a block movable within said slot, the opposite faces of said block being concaved, a spring bent upon itself at its longitudinal center and engaging the inner of said over-lapping ends, the arms of the spring passing through registering slots in said members, and having right-angled ends disposed in opposite directions and engaging one of the grooves in said block.
3. A spring frame for vehicle wheels, comprising two U-shaped members having sliding connections with each other and provided with oppositely disposed registering slots, the ends of the inner of said members being bent in opposite directions and overlapping each other, the ends of the outer member bent in opposite directions and against the outer face thereof, a block having oppositely disposed recesses, the contracted portions intermediate the recesses engaging registering slots in the members, a

coiled spring bent upon itself at its longitudinal center and engaging the inner of said overlapping ends, the ends of the spring bent at angles and engaging the inner face of said block.

35

4. A spring frame for vehicle wheels, comprising two U-shaped members having sliding connections with each other and provided with oppositely disposed registering slots, each having corresponding ends terminating in enlarged circular outlined portions, the ends of the inner member bent to over-lap each other, the outer over-lapping portion being concaved and the inner end formed into a hook, a block having contracted portions movable within registering slots in said members, the opposite faces of the block being concaved, a coiled spring bent upon itself at its longitudinal center and engaging said hooked end, the arms of the spring passing through registering slots in the members and terminating in angled ends engaging the grooved ends of said block.
